DISPENSING APPARATUS FOR CARBONATED BEVERAGES

Edward R. Taylor, Rocky River, Ohio

Application March 20, 1937, Serial No. 132,029

6 Claims. (Cl. 225—41)

This invention relates to dispensing apparatus for carbonated beverages, of the general type disclosed in my Patent No. 2,125,248, granted July 26, 1938, and the objects of the present invention are to provide improvements in said apparatus and particularly in a container having separate liquid and foam outlets, a faucet having separate liquid and foam controls and connections between such container and faucet.

As to the faucet, objects are to provide one having valves of plunger type controlled by a single handle, wherein the parts are inexpensively manufactured, easily assembled, and disassembled as for cleaning, and particularly wherein decarbonation of the liquid will be minimized, all as will appear. Other objects are to provide a simplified and otherwise improved container and connections therefrom to the faucet, wherein cleaning is facilitated and smooth flow of the liquid is had.

As beer is a characteristic liquid to be dispensed, for convenience specific reference will be made thereto only.

The exact nature of this invention together with further objects and advantages thereof will be apparent from the following description taken in connection with the accompanying drawing, in which Fig. 1 is a typical vertical section showing the parts assembled for operation, the valves being in closed position; Fig. 2 is a similar view of parts appearing in Fig. 1 but showing the beer valve as in open position; Fig. 3 is a transverse sectional elevation as in the planes of line 3—3, Fig. 1; Fig. 4 is a horizontal section in the planes indicated by line 4—4, Fig. 1; Fig. 5 is a transverse section as in the plane of line 5—5, Fig. 1; Fig. 6 is a detail in elevation of valve and cage parts appearing in Figs. 1, 2 and 3; Fig. 7 is a transverse section as in the plane of line 7—7, Fig. 6; and Fig. 8 is a face view of the outlet end of the faucet.

With reference now to the drawing, 1 is a valve body having a pair of ported valve seats 1a, 1a' in side by side relation, and separate inlet and outlet passages thereto and therefrom. These passages include, for the beer valve, a passage 1b leading from the central part of the inlet end of the valve body through the seat 1a and out through a nozzle part of the body as at 1c, and for the foam a passage 1b' leading from a cavity 1b'' annular about the inlet end part of the passage 1b, through the valve seat 1a' and out through the nozzle part of the valve body, separately from the beer passage 1c. The passages 1c and 1c' are preferably non-circular, as illus-

trated in Fig. 8, so that flow will be straight therethrough without whirl, and the streams will not spread upon leaving the nozzle.

The valve body 1 extends upwardly above the valve ports and is provided with parallel bores 1d and 1d', each aligned with one of the valve seats, these bores being of smaller diameter adjacent their valve seats than thereabove as indicated in Figs. 1, 2 and 3, the body being enlarged as at 1a to provide a cavity 1f communicating between the bores and closed by the removable cover 1g, and the body also having annular cavities immediately above the valve seats.

For each bore is provided a valve 2, 2', slideable in the lower part of the bore as a valve way and provided with a washer for sealing upon its seat, and thereabove a valve cage 3, the cage having upper and lower portions 3a and 3b slideable in the bore respectively above and below the cavity 1f. Each valve has detachable connection with its cage as by the threads indicated in Figs. 1 and 3. Sealing means such as the rubber gasket 4 backed by coiled spring 4a, being provided between the valve and cage and there effective between the valve and bore.

Each valve is yieldably urged to seated position by a spring 5 acting in compression between the upper end of its cage and a closure 6, suitable centering projections being provided for the spring, upon cage and closure as illustrated. The closure 6 preferably extends laterally to back both springs 5, and is detachably secured upon the valve body 1 as by a pair of screws as indicated in Fig. 3.

Means are provided for controlling both valves from a common handle 7 as follows: A rock shaft 8 of square or otherwise non-circular section, is mounted as by bushings 8a in the side walls of the body, to extend transversely through the cages 3 and project beyond the body where it fits in the yoke arms 1a of the handle, and is there retained as by the set screws indicated. For each valve a cam 9 is mounted on the shaft 8 within its cage, having a lobe engageable with the head end part 3a of the cage, which latter may be provided with a wear plate 3c adjustable as by a backing screw threaded in the cage to engage the end of the wear plate stem as illustrated, to be wiped by the cam, each cage having its end parts 3a and 3b joined in spaced relation by four post members 3e as best shown in Figs. 6 and 7, and the parts being so proportioned and arranged as to clear both shaft 8 and cams 9, the cams being located endwise on the shaft between pairs of posts 3d and the cavity 1f permitting

projection of their lobes beyond the posts. The cams 9 may be identical, disposed upon the shaft 8 in left and right relation.

The parts are so proportioned and arranged that when the handle 7 is in vertical position as illustrated in Figs. 1 and 3, both valves are maintained seated by their springs 5. When the handle is pushed rearwardly as in Fig. 2, the foam valve only is unseated by its cam 9, and when the handle is pulled forwardly from its closed upright position the beer valve only is unseated. The annular cavities in the valve bores above the valves 2 and 2' are in communication with the inlet passageways 1b and 1b' through the valve guiding portions of the body. It results therefore that when the faucet is opened unseating of the valve 2 carries the seal 4 from its lower position shown in Figs. 1 and 3 to its upper position shown in Fig. 2, thus placing the cavity chamber in communication with the inlet passageway so that beer or foam (depending upon which valve is open) flows upwardly into the annular cavity at the same moment that the associated valve is unseated. This permits the beer or foam to expend its pressure upwardly into the cavity at the moment the valve is cracked which prevents spitting at the faucet outlet. No appreciable expansion takes place on this flow into the annular cavities but it is merely an instantaneous outlet for the fluid pressure upwardly at the moment the valve begins to open.

For serving the faucet an auxiliary container 10 is provided, having a cover 11 with an inlet connection 12 for beer from a cooling coil, it being intended that the container 10 be submerged in a cooling liquid as more fully described in my above named patent. The cover includes a nozzle 12a so directing the inflowing beer that the latter will spread smoothly over a plate 13 within the container 10, to increase the exposed surface area of the beer stream with minimum turbulent effect upon the latter. The cover is provided with an outlet member 14 having a pair of passages 14a and 14b. The passage 14a, which is for beer, has a coil 14c connected to it and disposed within the container 10, terminating adjacent the bottom of the latter, the passage through this coil being somewhat smaller than the passage inlet 12 so that the coil forms sufficient choke against outflow from the container that pressure within the container will be maintained approximately independent of outflow of beer. The passage 14b which is for foam, leads from the upper end of the container chamber.

For connection between container and faucet, a straight beer tube 15 is provided leading directly from the end of the passage 14a in the container cover to the inlet end of the passage 1b in the faucet. This tube may be rigidly secured in the faucet and detachably inserted into the end of the container outlet 14 and there provided with a gasket 15a.

For separate delivery of foam from the container to the faucet, a pipe 16 is arranged about the tube 15 to provide an annular foam passage, leading from an annular cavity in the face of the container outlet 14 into which cavity the passage 14b delivers, to the annular cavity 1b' in the faucet body 1. For the purpose this tube 16 may be threaded into the faucet body, a sleeve 17 perforated as at 17a threaded upon its opposite end and secured to the container outlet 14 as by a collar 18, sealing gaskets illustrated in Fig. 1 being arranged to be effective between the sleeve 17 and its adjacent parts 14 and 16.

For mounting the faucet and container upon the wall A of a cooling box or the like, and through which the beverage is to be dispensed, the pipe 16 may be threaded as indicated to receive a nut 19 by which the wall A is clamped between the nut and the inlet end of the faucet, the latter being preferably provided with the flange indicated and the usual washer provided under the nut.

It will be apparent that the beer passage throughout the apparatus is as direct and smooth as possible so as to provide least disturbance to beer flow with a minimum of beer turbulence.

It will also be noted that all parts are easily disassemblable for thorough cleaning.

In servicing the faucet, removal of the cap 6 permits removal of the springs 5. Thereafter removal of the handle 7 from the shaft 8 permits its endwise withdrawal, and removal of the cover 1g permits removal of the cams 9, whereupon the cages with their valves may be withdrawn from their bores for replacement of the valve washers, and the valves detached from their cages as for replacement of the gaskets 4.

While reference herein is made to beer and foam as the fluids to be handled, it will be understood that my invention is not limited by application to any particular beverage other than that said beverage be of the carbonated type. Thus the invention is equally applicable to non-alcoholic beverages such as gingerale, as to the beer mentioned throughout herein for convenience.

What I claim is:

1. In a faucet for the purpose described, a body having a pair of valve seats and separate passages therefor having separate outlets, valves for said seats, and control means for said valves arranged to have a closed position wherein both valves are seated, and for each valve an open position wherein that valve only is unseated.

2. In a faucet for the purpose described, a body having a pair of bores each providing a valve way with a valve seat, said body having separate passages for said seats, a cage slidable in each bore and a valve in each way attached to one end part of its cage, a shaft mounted in said body and extending transversely through both said cages, a cam mounted on said shaft within each cage, and arranged to move the latter to unseat its valve, a handle arranged to control said shaft, said cams being so arranged that said handle has a closed position wherein both valves are seated, and for each valve an open position wherein that valve only is unseated.

3. In a faucet for the purpose described, a body having a bore providing a valve way with a valve seat, a cage slidable in said bore and a valve in said way attached to said cage, a shaft mounted in said body and extending transversely through said cage, a wear plate adjustably mounted on said cage, a cam mounted on said shaft within said cage and arranged to bear upon said wear plate to move said cage to unseat said valve, and a handle arranged to control said shaft.

4. In a faucet, a body having a valve seat, a valve coacting with said seat, there being fluid inlet and outlet passageways in said body leading respectively to and from said valve seat, there being a chamber of limited capacity in said valve body communicating with said inlet passageway, means operable by valve movement and closing off said chamber communication when said valve is closed, and said means being arranged to establish communication between said chamber and

inlet passageway by opening movement of said valve.

5. In a faucet, a body having a bore providing a valve way with at valve seat, a valve in said way coacting with said seat and openable against fluid inlet pressure, there being fluid inlet and outlet passageways in said body leading respectively to and from said valve seat, there being an annular cavity in said bore in communication with said 10 inlet passageway, sealing means in said cavity and movable with said valve, said sealing means preventing fluid flow into said cavity when said valve is seated, and said sealing means being movable with said valve when it is opened to permit 15 fluid flow into said cavity, whereby fluid under pressure flows into said cavity at the instant said valve is opened minimizing spitting at said outlet

passageway when said fluid is under pressure.

6. Means for interconnecting separate beer and foam passages between a container and faucet, comprising a cylindrical tube of smaller diameter connecting said beer passages, a cylindrical tube 5 of larger diameter surrounding said smaller tube and providing an annular passage, means connecting said annular passage with said foam passages at both container and faucet ends thereof, whereby beer flows smoothly through the central 10 passage and foam follows the more turbulent passage through the annular passage and its connecting means, and rotatable connections between said cylindrical tubes and said container 15 and faucet.
